(57) **CLAIM**

The ornamental design for an endoscope, as shown and described.

DESCRIPTION

FIG. 1 is a perspective view from the front side of an endoscope showing our new ornamental design;

FIG. 2 is a perspective view from the rear side thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The tube shown in FIGS. 1-8 is drawn broken away to indicate that no particular length is claimed.
